UNITED STATES PATENT OFFICE

115,772

DESIGN FOR A PAIR OF SPECTACLES

Edward M. Splaine, Southbridge, Mass., assignor to American Optical Company, Southbridge, Mass., a voluntary association of Massachusetts

Application March 24, 1938, Serial No. 76,059

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Pair of Spectacles, of which the following is a specification, reference being made to the accompanying drawing, forming a part thereof.

Fig. I is a perspective view of a pair of spectacles embodying my design;

Fig. II is a top or plan view of the spectacles shown in Fig. I;

Fig. III is a fragmentary sectional view taken on line III—III of Fig. II and looking in the direction of the arrows; and

Fig. IV is a fragmentary sectional view through the mounting and a portion of the lens taken on line IV—IV of Fig. II and looking in the direction of the arrows.

The temples have been shown in a fragmentary

condition in Figs. II, III and IV for convenience of illustration.

The characteristic features of my design, which are shown in full lines in the drawing reside in the provision of relatively long slender bar-like members shaped substantially to the upper contour of the beveled lenses and having a substantially triangular cross sectional shape intermediate the ends thereof with the narrowest edge toward the front and the horizontal and perpendicular surfaces thereof lying substantially in the same planes.

The bar-like members are shaped and proportioned to blend with each other and with the other parts of the mounting.

The essential features of my design are shown in full lines.

I claim:

The ornamental design for a pair of spectacles, substantially as shown and described.

EDWARD M. SPLAINE.
